UNITED STATES PATENT OFFICE.

RANDALL T. VAN VALKENBURG, OF NILES, MICHIGAN.

ATTACHMENT FOR SINGLETREES.

SPECIFICATION forming part of Letters Patent No. 532,119, dated January 8, 1895.

Application filed March 13, 1894. Serial No. 503,521. (No model.)

To all whom it may concern:

Be it known that I, RANDALL T. VAN VALKENBURG, a citizen of the United States, and a resident of Niles, in the county of Berrien and State of Michigan, have invented a new and useful Attachment for Singletrees, of which the following is a specification.

This invention relates to certain new and useful improvements in attachments for singletrees, and has for its object to provide means for preventing the traces or tugs of the harness from accidentally becoming detached from the singletree, thus avoiding runaway accidents which are often caused thereby; further to provide a support for the ends of the traces or tugs which are often longer than necessary, from flopping about and coming in contact with the wheels of the carriage; and means to regulate the swinging movement of the singletree, caused by the movement of the horse, as well as to hold the singletree intact, should one of the traces or tugs become detached therefrom, thus dispensing with the unreliable leather straps or loops which are usually used for the same purpose, and which become rotten and useless through long usage.

The attachment is simple and inexpensive, and entirely avoids the dangerous accidents often caused by a trace becoming detached from the singletree, or the end of a tug coming in contact with the wheels of a carriage, making a rattling noise, and frightening the horse.

With this object in view, the invention consists of the construction and arrangement of parts as will be hereinafter described and claimed.

In the drawings, Figure 1, shows the manner in which my invention is attached to a singletree. Fig. 2, shows a perspective view of the same, and Fig. 3, shows a modified trace or tug supporter on the attachment.

Referring to the drawings, the numeral 1 designates my attachment consisting of a metallic strip 2, formed on its outer end into a curved plate spring 3, having a downwardly projecting end 4, the point of which enters a depression 5 in the singletree. In fastening the ends of the traces or tugs to the singletree, the end of the spring 3 is raised a sufficient distance to allow the tug to be slipped

over the end of the singletree and under the spring, when the same is released, and it assumes its original position.

6 is a trace or tug supporting loop centrally affixed to the strip 2 by a laterally projecting curved portion in any suitable manner, the end of the tug being inserted through the loop after the same is fastened to the singletree, (see Fig. 1,) and thus prevented from flopping about.

Instead of having a loop for holding the ends of the tugs, a flexible hook 8 as shown in Fig. 3, may be provided, which will clamp and hold the ends of the tug or trace firm when forced between the sides thereof.

To the inner end of the strap 2, is fastened a spring hook 9, the end of which impinges against the cross bar connecting the thills of a buggy, (as shown in Fig. 1,) and obviates the necessity of singletree straps or loops to regulate the play of the singletree; the spring hooks also preventing the abrupt and jerky movement of the singletree occurring when leather straps or loops are used for the same purpose, and which on rough and uneven roads, causes the breast collar, which is connected with the singletree by the traces or tugs, to rub and consequently chafe the horse, through the swinging motion of the singletree caused by the movement of the horse being stopped too abruptly.

In order to prevent the spring hook 9 from marring the cross bar 10, a leather strip 11 is affixed to the same against which the spring hooks impinge.

The attachment may be fastened to the singletree by screws, bolts, or in any other suitable manner.

The attachment as herein described, if desired, can be manufactured out of one piece, or the tug supporting loop 6, the hook 9 and the strip 2, with the spring formed on one end, manufactured separately and connected together by screws or bolts which at the same time secures the attachment to the singletree.

Having thus described my invention, what I claim as new, and desire to secure by Letters Patent, is—

The combination in an attachment for singletrees comprising the metallic strip formed on the outer end into a curved spring having

a downwardly projecting point, a trace or tug supporting loop laterally affixed to said strip at or near the center thereof, and the spring hook secured to the inner end of the strip to 5 impinge against the cross bar and regulate the movement of the singletree, substantially as described.

In testimony that I claim the foregoing as my invention I have signed my name in the presence of two subscribing witnesses.

RANDALL T. VAN VALKENBURG.
